UNITED STATES PATENT OFFICE

113,378

DESIGN FOR A LIQUID DISPENSER CABINET

Donald Colvin, San Francisco, Calif.

Application December 19, 1938, Serial No. 81,873

Term of patent 3½ years

To all whom it may concern:

Be it known that I, Donald Colvin, a citizen of the United States, residing in the city and county of San Francisco, and State of California, have invented a new, original, and ornamental Design for a Liquid Dispenser Cabinet, of which the following is a specification, reference being had to the accompanying drawings, forming part thereof, in which:

Figure 1 is a front elevation of a liquid dispenser cabinet embodying my new design; and

Figure 2, an end elevation thereof as viewed from the right end of Figure 1.

Both ends of my liquid dispenser cabinet are identical. The stippling in the drawings indicates contrast between the cabinet and the hardware fittings.

I claim:

The ornamental design for a liquid dispenser cabinet, substantially as shown and described.

DONALD COLVIN.
